UNITED STATES PATENT OFFICE

URBAN C. THIES, OF DAYTON, OHIO, ASSIGNOR, BY MESNE ASSIGNMENTS, TO THE GLOBE-WERNICKE COMPANY, OF CINCINNATI, OHIO, A CORPORATION OF OHIO

DOOR AND DOORWAY

Application filed July 28, 1930. Serial No. 125,540.

This invention relates to sheet metal doors, and the especial object is the provision of a door which may be reversed so that it may operate either as a right or a left door, and thus open in one direction with its hinge located either at the right or at the left of the door.

A further object of the invention is the provision of a door which is constructed of 10 sheets of metal, the door being made in two halves which are attached together at the plane of symmetry of the door. Each half of the door is composed of vertical stile members and horizontal rail members, each 15 of which is made up of individual sheets of metal. The various sheets of metal are rigidly united together in each of the door halves by means of angle plates provided at the junctions of the stile and rail members. These angle plates are formed of 20 flanged metal sheets which are placed in contact with the outer flanges of the door stiles and rails and are either riveted or welded rigidly to both parts of the door to 25 rigidly unite them together. The two halves of the door are made as units and then integrally united together by welding or by soldering. One of the door stiles is provided with a lock and latch casing which 30 is insertable through the side end of the door and the other stile is provided with hinges insertable through the door in a reversible manner so that by a mere reversal of the hinges and the parts of the lock and 35 latch casing the door may be converted from a right to a left-hand swing door and vice versa.

In order to permit the reversal of the door the door jamb is likewise made so that it is 40 adapted to accommodate either a right or a left hand swing door. For this purpose the door jamb which supports the hinges cooperates with the door in such a manner that the door jamb may be reversed end for end 45 and for this purpose the hinges are provided with symmetrically spaced attaching holes and the hinges themselves are evenly spaced from the center of the door jamb. The door jamb which cooperates with the door latch and lock is provided with a latch hole located

centrally so that it may cooperate with the latch of the door with this latch located in either of its reversed positions, the latch of the door having its center located in the plane of symmetry of the door so it will fit 55 into the latch hole of the door jamb in either of its positions.

The reversible door is especially adapted for use in sheet metal partitions and in other sheet metal building construction of similar 60 nature. Other objects and advantages of my invention will be more fully discussed in the following specification, in the attached claims and in the accompanying drawings, of which;

Fig. 1 is an elevation of one of the door sections.

Fig. 2 is a horizontal section on the line 2-2 of Fig. 1.

Fig. 3 is a detail of an angle plate of the 70 door.

Fig. 4 is a perspective detail showing the manner of attachment of the door hinges.

Fig. 5 is a central horizontal section through the door and the door way.

Fig. 6 is an elevation of a door as applied to a partition.

Fig. 7 is a perspective view of an end of the door jamb which receives the hinges.

Fig. 8 is a perspective view of the end of 80 the jamb which cooperates with the latch of the door.

Fig. 9 is a detail of an end of one of the partition units.

Fig. 10 is a perspective view of the unit 85 end shown in Fig. 9.

Fig. 11 is a view of the side end of the door showing the lock and latch casing.

Fig. 12 is a side view of the latch casing.

Fig. 13 is a vertical section through the 90 lock cylinder of the latch casing.

Referring more particularly to the drawings by reference numerals, the door 1 is constructed of two similar halves which are joined together along their abutting edges. 95 One of the halves is indicated at 2 in Fig. 1, and is there shown as comprising the two vertical stile members 3 and 4 which are each bent from one piece of sheet metal having upwardly and inwardly bent flanges on 100

the outside and the inside of the stiles as indicated at 5 and 6. The outer flange 5 is cut away at an intermediate part of the lock stile 3, and the inner flanges 6 are cut away at the ends of the stile as indicated in Fig. 1.

The three door cross rails 7, 8, and 9 are each constructed of a single sheet of metal and provided with upwardly and inwardly extending flanges throughout their lengths as indicated at 10 and 11. The various stile and rail members of the door section are placed in abutting relation and then rigidly united integrally by the provision of angle plates 12, 60, 61, 62, 63, and 64, which are made of flat sheets of metal having upwardly bent sides such as 13, and on plate 12 one of these sides may be bent over at 14 to complete the inwardly extending flanges 15 of the door end. These corner angle plates are integrally united to each of the members with which they are in contact, preferably by means of solder or by spot welding, and hold the stile members rigidly to the 20 rail members. The angle plate 61 in the vicinity of the latch casing 16 is cut away at its outer side to permit the insertion of the latch casing through the side end of the door. This latch casing is provided with 25 lugs 17 for the reception of screws 18 which are counter-sunk in the outer sides of the door stile and thread into these lugs. The latch casing 16 is spaced centrally in the plane of symmetry of the door by means of 30 spacing lugs or angle irons 19 which are rigidly attached to the door sections and between which the latch casing is adapted to be moved into place or to be removed.

It will be noted that the bottom rail member 9 is of greater vertical height than the intermediate and the top rail and the angle plates 12 and 60 at the bottom of the door are consequently made of larger size so as to extend completely over the joints between 40 the rail and the stile members. The three angle plates 12, 62 and 63 along the stile 4 and the stile itself are slotted as indicated at 20 so that the slot is immediately adjacent to the upwardly extending flanges on said 45 single plates. These slots permit the insertion of a hinge leaf 21 after the two door sections have been rigidly united together. The door sections are united by spot welding along the plane of symmetry of the door 50 where these two sections abut together and any cracks or small spaces which may exist between the two sections along the sides of the stiles and rails may be filled in with solder so as to produce a smooth surface. 55 After the two sections of the door have been assembled a pair of glass retaining strips 55 may be attached to the inner sides of the stiles and rails by means of screws 65 received in the inner sides of the stiles and 60 rails and extending through suitable holes

in the strips 55, and similar panel retaining strips applied for retaining the lower sheet metal panel of the door.

The hinge side 21 is provided with six symmetrically arranged tapped holes 22 and the side of the stile 4 is provided with six correspondingly arranged counter-sunk holes 23. The holes 23 are equi-distantly spaced apart and from the sides of the door so that the hinge part 21 may be inserted 70 from either side of the door so as to extend completely through the door and have its end flush with the side of the door opposite to the hinge pin. The three hinges with which the door is provided are equi-distantly and symmetrically spaced apart, the center hinge being located close to the center of the door so that the hinges may cooperate with the hinge jamb of the door way to permit the reversal of the hinge jamb as will be 75 later set forth. The center of the middle hinge slot 20 is indicated by the line 24 which is coincident with the center of the latch 25 of the latch casing. The latch 25 has its center located in the plane of symmetry 80 of the door as indicated in Figs. 5 and 11, and the vertical height of the latch is such that the latch hole 38 with which the latch cooperates is provided in the longitudinal center of the door jamb 26. This door jamb 85 is shaped as shown in Fig. 8 so as to have a mounting surface 27 provided with a series of attaching holes 28 which are symmetrically spaced along the door jamb and which are adapted to cooperate with the attaching 90 holes 29 provided in the flanges 31 of the uprights 30 which are constructed and arranged in pairs as more fully set forth in my prior application for United States Letters Patent, Serial No. 89347, filed February 19, 1926, and entitled "Partition units and construction". The partition of which the doorway forms a part is constructed of similar units 30 and panel pieces 32, these units being provided with attaching curl-plate extensions 33 as set forth in my prior application referred to, these curl extensions having a length equal to or slightly less than one-half of the width of the units 30 and being provided in opposing pairs on each 100 end of the various units so that the units may be arranged as uprights and as cross-rails with their ends attached together by through pins 34 which extend through a complete pair of partition units. The units 105 are provided with one side which is open along its center and which is provided with inwardly extending flanges 35 having groups of attaching holes 29 symmetrically spaced from the ends of the units and each 110 group consisting of a small hole for the reception of attaching screws and a large hole adapted to receive the head of a screw which attaches a panel to an opposing and mating unit. 115

The doorway is defined by the door jambs 36, 26, and top jamb 37, these three pieces being held between the pairs of mating units 30 as indicated in Fig. 5. The face 27 of the door jamb 26 has its holes 28 symmetrically arranged in the same manner as the placing of the holes 29 in the units 30 so that the door jamb 26 may be bolted in place to one side flange of one of the units 30. The various pairs of units are attached together at their ends by means of the pins 34 and the screws 39 which are threaded into the ends of these pins and which are counter-sunk in a rectangular end plate at each of the junctions of horizontal and upright members.

The door jamb 26 extends at right angles to the surface 27 then outwardly, forwardly, inwardly, and forwardly so as to provide a stop for the door as indicated at 40 and a vertical surface 41 in which the latch hole 38 is provided. The surface 40 is turned inwardly and rests against the edge of the unit 30 adjacent thereto. The latch hole 38, being provided in the longitudinal center of the door jamb 26, permits the reversal of the door jamb end for end so that the door jamb may stop the door from moving toward either side of the door. The surface 27 and the surface 42 in the same plane are both located in the plane of symmetry of the assembled pairs of partition units 30, and the latch hole 38 is provided in the transverse center of the surface 41 so that it may co-operate with the latch in either of its positions.

The door jamb 36 is made similar to the door jamb 26 just described but is adapted for the reception of hinge parts which are insertable through the slots 43 so that the hinges may be rigidly attached to the jamb. The slots 43 are equi-distantly spaced and symmetrically arranged, the center slot being located in the center of the vertical height of the jamb so that the jamb may be reversed end for end to permit the door to operate as a right or as a left hand swing door, and to open toward either side. The slots 43 in the jamb are so located that the hinge part after being inserted through the slots lies against the inner part of the vertical face 44 of the jamb. This face is provided with counter-sunk screw holes 45 symmetrically arranged as shown so that the hinges may be inserted when the door jamb has been reversed. The upper jamb 37 is also made reversible by the symmetrical spacing of the attaching holes provided in the surface which is clamped and held between the flanges of opposing pairs of units which make up the cross rail 46 above the door. This cross rail 46 is preferably not constructed of a single pair of units but is made of two or three shorter hollow units exactly similar except as to length to the

units 30, these smaller sections being attached together by through pins 34, screws 39, and square cover plates 47. The cover plate 47 may be specially made so that it supports the stationary part of the door closer, the other part of the door closer being mounted upon the door adjacent thereto in any suitable manner.

The latch casing 16 is shown in Figs. 11, 12, and 13 as consisting of a casing 48 provided with the attaching lugs 17 and having a knob lock part 49, lock cylinder openings 50, latch 25, and dead lock stop for the latch 51. The various parts of the lock are made reversible so that when the door is to be changed to open towards the other side the latch may be reversed so that its inclined surface faces toward the other side of the door, and the lock cylinder 52 reversed with the dummy cylinder 53. The dead lock stop is also reversible in the lock itself so that the entire lock and latch casing may be adjusted to permit its use in a door adapted to open in either direction. A knob 54 is adapted to turn the latch and a key plate 55 is provided on the outside of the dummy cylinder and on the lock cylinder. In order to provide for the insertion of the lock and dummy cylinder, and for the knob spindle, the halves of the door are provided with holes 54 through which these parts may be inserted.

The doors are preferably constructed of sheet metal and are preferably hollow but if desired to afford greater fire protection the two halves of the door, before being attached together, may be placed horizontally and filled with suitable fire proofing composition which may solidify sufficiently to be retained in the door sections during their assembly. Any suitable compound may be used.

It will thus be apparent that in order to change a door swinging outwardly about a hinge at the right of the door as shown in Fig. 5 the two door jambs and the top jamb may be reversed end for end by first removing the upright units 30 which are not attached to the inwardly extending faces of the jambs. The hinges of the door are taken out of one side of the door and inserted into the other side of the same and the latch casing is removed by the removal of the attaching screws 18 which permits the latch casing to be withdrawn from the side of the door stile; the various parts of the lock and the latch casing are then reversed and adjusted so that the parts are adapted to a door which operates in the reverse manner from that indicated in Fig. 5. The hinges are then replaced in the inverted door jamb 36 and the complete change or reversal of the door is then effected. The provision of the latch in the plane of symmetry of the door and the manner in which the hinges may be inserted from either side

- and the fact that the door is equipped with a latch casing capable of having its parts reversed permits the door to be completely changed from a right to a left hand swing door and vice versa. The provision of the latch hole and the provision of the hinge slots in the door jambs permits these parts to be reversed end for end and cooperate with the same door.
- 10 It will be understood that various changes and modifications may be made without parting from the spirit or scope of the invention and I do not intend to be limited to the precise construction which has been chosen herein for purpose of illustration.
- 15 What I claim is:—
1. A sheet metal door having detachable hinges and attaching means for detachably securing said hinges in position, said hinges and door having attachment provisions cooperating with said attaching means for the attachment of said hinges in a reversible manner so that the hinge pin may be located on either side of the door.
  - 25 2. A sheet metal door having slots for the reception of door hinges, said slots extending entirely through the door, and attaching holes in the side edge of said door symmetrically arranged so that the hinges may be inserted from either side of the door and fastened to the side edge thereof so that the door may be adapted to open from either side.
  3. In a door of the class described, a series of attaching hinges for said door, said door being provided with a corresponding series of slots extending entirely through the door and with holes in the side face thereof arranged in spaced pairs with the holes of each pair horizontally spaced apart and at equal distances from the adjacent side edge of the door so that the hinges may be inserted into the door from either side thereof and then fastened in place.
  - 45 4. A sheet metal door having a latch casing insertable through the side end of the door, the center of the latch being located in the plane of symmetry of the door, means for detachably and reversibly attaching said latch casing in the door, said latch having reversible parts so that said door may be adapted to open from either side a plurality of hinges for said door, attaching screws for detachably securing said hinges to said door, said hinges and door having attachment holes cooperating with said attaching screws for the attachment of said hinges in a reversible manner so that the hinge pin may be located on either side of the door.
  - 50 5. A sheet metal door having a lock and latch casing insertable through the side end of the door, the center of the latch being located in the plane of symmetry of the door, bolts passing from the sides of the door into said casing to detachably and re-

versibly attach said casing in position, said lock and latch casing having reversible parts so that said door may be adapted to open from either side, and a series of hinges for said door adapted to be attached thereto in a reversible manner.

6. A sheet metal door having a latch casing provided with reversible parts so that said latch may face in either direction, the center of the latch being located in the plane of symmetry of the door, and means detachably fastening said latch casing in position, said doors having provision for the attachment of hinges in a reversible manner so that the hinge pins may be located on either side of the door for the purpose described.

7. A sheet metal door having a latch casing and means for attaching said casing to the door substantially centrally in a vertical direction, the said latch being adapted to be reversed, said door having attaching hinges adapted to be reversed, and attaching holes for said hinges arranged symmetrically so that said hinges may be mounted on the door in either position.

8. A sheet metal door constructed of sections joined together, said sections each being made up of separate vertical stile members, separate horizontal rail members, and angle plates at the joints between the rail members rigidly attached to each of said members and lying flat against the inner surfaces of the stile and rail members.

9. A sheet metal door constructed of similar halves abutted together and rigidly welded together along the plane of symmetry of the door, said halves each being made up of separate stile and rail members, and flanged angle plates welded to the stile and rail members to rigidly unite them together.

10. A sheet metal door constructed of similar halves joined together, hinged pieces passing through the door and through each of said halves, and lying inside of the side edge of the door, and means attaching each hinge piece to each of said halves.

11. A sheet metal door constructed of similar halves abutted and attached together, hinge pieces passing entirely through the door and lying inside and against the inner side edge of the door, the said edge of the door having attaching screw holes symmetrically arranged so that said hinges may be attached to the door in a reversible manner.

12. A sheet metal door constructed of similar halves welded together along the plane of symmetry, and hinge pieces passing through the door and through each of said halves, and lying inside of the side edge of the door, said hinge pieces and the door edge having symmetrically arranged attaching holes, the hinge being reversibly attach-

- able to the door so that the door may be adapted to open toward either side, said hinges being symmetrically spaced apart.
13. In combination, a doorway formed of a pair of vertical door jambs and a top jamb, a set of hinges supported from one of said jambs, a door on said hinges and attachable thereto in a reversible manner so as to be adapted to be reversed to be opened toward either side, said hinges being evenly spaced apart along said door jamb so as to permit the door jamb to be inverted for the purpose described.
14. In combination, a door having reversible latch means and reversible hinges so that it may be adapted to be opened toward either side, and a doorway cooperating with said door and having reversible parts adapted to cooperate with said latch means and said hinges to permit the door to be opened toward either side.
15. In combination, a hollow metal door formed of permanently united sheets of metal, a latch casing housed within a stile of the door, spacing lugs rigid with each side of said stile to space the latch casing in a central position, attaching screws passing through the side of the stile into the latch casing, latch operating means, each side of the stile being provided with a hole for the latch operating means, both sides of the said stile of the door being similar in construction so as to permit the reversal of the latch parts for the reversal of the door.
16. In combination, a hollow metal door formed of permanently united sheets of metal, a latch casing housed within a stile of the door, attaching screws passing through the side of the stile into the latch casing, latch operating means, each side of the stile being provided with a hole for the latch operating means, both sides of the said stile of the door being similar in construction so as to permit the reversal of the latch parts for the reversal of the door, said latch being located in the plane of symmetry of the door and said door having insertable hinges insertable through either side of the door for the purpose described.
17. A sheet metal door constructed of halves abutted and joined together, said halves being formed of separate stile and rail members, plates of metal rigidly united with said stile and rail members to join the same together, hinge slots extending entirely through the door and extending through said plates of metal for the reception of hinges.
18. A sheet metal door constructed of halves abutted and joined together, said halves being formed of separate stile and rail members, plates of metal rigidly united with said stile and rail members to join the same together, hinge slots extending entirely through the door and extending through
- said plates of metal for the reception of hinges, said plates of metal having flanges extending along the side edge of the door and against the same and being located between the hinge parts and the said side edge of the door to reinforce the same.
19. A sheet metal door jamb having a longitudinal vertical side having attaching holes therein by means of which it may be fixed in position, said jamb being bent in several places to provide a hollow four-sided jamb member and then bent to extend parallel to the door edge from said jamb member, and terminating in a reversely bent curved portion extending substantially 90° from said first-mentioned vertical side.
- In testimony whereof I have hereunto set my hand this 27th day of July 1926.
- URBAN C. THIES.
